UNITED STATES PATENT OFFICE.

CHARLES EDWARD SPIGELMIRE, OF SPARROWS POINT, MARYLAND, ASSIGNOR TO
BETHLEHEM STEEL COMPANY, A CORPORATION OF PENNSYLVANIA.

LIQUID-FUEL BURNER.

Application filed March 15, 1922. Serial No. 543,923.

The present invention relates to burners for liquid fuel and particularly to burners for vaporizing crude oil or tar and delivering the resulting combustible gas directly 5 into furnace combustion chambers.

Burners constructed in accordance with the present invention are particularly adapted to withstand the intense heat of such combustion chambers, while at the 10 same time the use of special heat insulating materials, water jackets, etc., is avoided, the burner being cooled by the same fluid, which may be either air under pressure, or steam, which is used to gasify the liquid fuel supplied 15 and to propel the gaseous mixture into the furnace combustion chamber. The burner is provided with means for varying the shape of the flame delivered so that the operator is enabled to project a flame into 20 the furnace which may be flat or fan-shaped in either a vertical or a horizontal direction, or which may have the irregular whirling or rotating motion now frequently used. The burner is extremely simple in its details 25 of construction, the various parts being so arranged with respect to each other that no strains are set up due to the expansion and contraction resulting from changes of temperature, and so that it may be constructed 30 and repaired with a minimum of trouble and expense.

In the accompanying drawings,

Fig. 1 is a longitudinal axial section through the burner;

Fig. 2 is a section on line 2—2 of Figure 1;

Fig. 3 is a plan and end view of the nozzle end of the liquid fuel supply tube;

Fig. 4 is a plan and end view of the nozzle of the burner; and

Figs. 5, 6 and 7 are diagrams illustrating different relative positions of the fuel tube nozzle and the burner tip.

The burner comprises essentially a hollow head casting 10, having aligned apertures in its end walls, a bushing 11 provided with a central cylindrical aperture which is aligned with the apertures of the head 10, and four concentric tubes 12, 13, 14 and 15 extending between the head and bushing. The outermost tube 12 comprises a casing member 45 for the burner and has one end secured to head 10 and the opposite end secured to the bushing by means of a sleeve 16.

The three inner tubes each have one end 50 entirely free. The innermost tube 15 con-

stitutes the liquid fuel delivery tube, having its inlet end secured to a fuel supply pipe 17 which may be connected to any suitable source of supply. Supply pipe 17 is supported by the coupling 18 which in turn as 60 shown has threaded engagement with the end of tube 13 projecting without the hollow head. Tubes 13 and 14 constitute baffle tubes, tube 13 being supported by the head 10 and tube 14 by the bushing 11, the last 65 mentioned tube as shown extending completely through the central aperture of the bushing and having threaded upon its projecting end the burner tip 19.

The orifice 20 of the burner tip 19 is, as 70 shown in Figure 4, relatively long and narrow and the forward end of the liquid fuel tube 15 is also flattened to provide a delivery orifice 21, similar in shape, though considerably smaller, than the orifice 20. 75 The two orifices 20 and 21 may be arranged with their major axes in different angular relationships by rotation of the fuel supply tube 15, which rotation may be effected by turning pipe 17. In Figures 5, 6 and 7, 80 three possible relationships are diagrammatically illustrated.

In the operation of the burner saturated steam is led through a pipe 22 into the interior of the hollow head 10. The steam 85 flows from the head and is caused to take a tortuous course by the baffle tubes 13 and 14 which direct it first forwardly along the inner wall of the casing 12, thence rearwardly between baffle tubes 13 and 14 and 90 thence again forwardly between baffle tube 14 and fuel supply tube 15. In this passage through the burner the steam exerts a cooling action upon the highly heated casing 12 and at the same time it becomes super- 95 heated so that as it passes forwardly in contact with the liquid fuel supply tube 15 it will heat, liquefy or reduce the viscosity and vaporize more or less the crude oil or tar within this tube. When the steam and 100 liquid fuel come in contact with each other in the mixing chamber 23 which lies within tube 14 and in advance of the fuel orifice 21, it completely gasifies the liquid fuel. The burning of the combustible mixture 105 which issues from the orifice 20 is very complete and practically is no loss experienced by reason of incomplete combustion resulting from incomplete vaporization of the liquid fuel.

From the structure described it will be apparent that the telescopic tubes 13 and 14 define a multiple-pass passage to conduct saturated steam or air along the interior of the casing 12 and then along the exterior of the fuel tube 15. This arrangement for a tortuous passageway for the vaporizing fluid assures that the relatively cool entering fluid, such as saturated steam or air, shall flow along the interior of the casing 12 in order to prevent the latter acquiring an excessive temperature. In its passage along the interior of the casing 12, the fluid is heated due to the absorption of heat from the casing, it then reverses and passes between the tubes 13 and 14, reverses again and then passes along the fuel tube 15. In this way, fluid which has absorbed heat from the casing 12 is brought into contact with the fuel tube 15 in order to liquefy or vaporize combustible liquid passing therethrough. This arrangement, therefore, provides for the entrance of fluid, such as steam, which shall pass along a surface of the element to be cooled; and, the cooling fluid absorbs heat from the element to be cooled and then passes along an element to be heated, such as the fuel pipe. This apparatus, therefore, assures that the outer casing of the burner shall not attain too high a temperature and at the same time utilizes heat absorbed by the cooling fluid in raising the temperature of the fuel entering the burner through the fuel pipe.

In the drawing the burner is shown broken away, for convenience. It is to be understood however that it may be of any desired length and that by selecting a suitable length any desired amount of surface for heating the steam or air and fuel may be obtained.

Compressed air may be utilized in place of steam where conditions warrant its use. It will be apparent to those skilled in the art that modifications may be made in the design and arrangement of the component parts of the invention without departing from its scope.

Having thus described the invention what is claimed as new and desired to be secured by Letters Patent is:

1. In a fuel burner, the combination of a burner tip, a mixing chamber communicating with the burner tip, a fuel tube adapted to discharge fuel into the mixing chamber,

a casing for supporting the fuel tube and the burner tip in predetermined relation, means cooperating with the casing and defining a passage therealong which has an inlet for steam adjacent to the end of the casing remote from the burner tip, and means cooperating with the fuel tube to define a passage for discharging steam into the mixing chamber, said two means cooperating to define an intermediate passage which affords communication between the first and second passages.

2. A fluid burner comprising in combination, a tubular casing, a fuel tube within said casing, a second tube spaced from and surrounding said fuel tube and forming an inner annular passage and providing a mixing chamber at the tip of the fuel tube, a third tube surrounding said second tube forming an exterior annular passage between its exterior surface and the casing, and an intermediate annular passage between its interior surface and the second tube, said exterior passage at one end being in communication with a supply of fluid, and at its other end with the intermediate passage, the opposite end of the intermediate passage being in communication with the inner passage and the latter at the tip end of the burner being in communication with said mixing chamber.

3. In a liquid fuel burner, in combination, a liquid fuel delivery tube having an elongated delivery orifice, a burner tip coaxial therewith and having an elongated delivery orifice, said tip and fuel delivery tube being relatively rotatable so that the major axes of said orifices may be brought into any desired angular relationship.

4. In a liquid fuel burner, in combination, a hollow head member and a bushing member spaced therefrom, a tubular outer casing rigidly connecting the head member and bushing, three concentric tubes within said tubular casing, the innermost tube comprising a fuel delivery tube having a delivery orifice adjacent the bushing, and the two intermediate tubes comprising baffle tubes, one of which is entirely supported from the head and the other of which is entirely supported from the bushing, and means for conducting steam to said head.

In testimony whereof I hereunto affix my signature.

CHARLES EDWARD SPIGELMIRE.
